Primary Examiner — Philip S Hyder*Assistant Examiner* — Sydney R Buffallow(74) *Attorney, Agent, or Firm* — Banner & Witcoff, Ltd.(57) **CLAIM**

The ornamental design for a cooler, as shown and described.

DESCRIPTION

FIG. 1 is a front right perspective view of a cooler showing our new design;

FIG. 2 is a top view thereof;

FIG. 3 is a front view thereof;

FIG. 4 is a right view thereof;

FIG. 5 is a left view thereof;

FIG. 6 is a rear view thereof; and,

FIG. 7 is a bottom view thereof.

The broken lines shown in the drawings are directed to environment, and are for informational purposes only and form no part of the claimed design.
